UNITED STATES PATENT OFFICE.

EARL A. SHANKWEILER, OF ALLENTOWN, PENNSYLVANIA.

LOUD SPEAKER.

Application filed December 7, 1925. Serial No. 73,752.

This invention relates to a loud speaker designed primarily for use in connection with radio receiving sets, one of the objects of the invention is to provide a loud speaker 5 in the form of a pedestal which can be used for supporting a lamp or other object and the construction of which is such as to insure the clear reproduction of the tones without objectionable vibrations.

10 A further object is to provide a loud speaker which will constitute an ornamental article of furniture.

It is well known to those skilled in the art that best amplifying results are obtained by 15 the use of a long sound chamber the walls of which are formed of a resonant material such as wood. It has not been possible, heretofore, to ordinarily embody these features in loud speaker constructions.

20 It is an object of the present invention to provide an article of furniture in which a sound chamber having the foregoing qualities can be produced.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings the preferred form of the invention has been shown.

In said drawings,

Figure 1 is a front elevation of the device. Figure 2 is a section on line 2—2 Figure 1.

Figure 3 is a section on line 3—3 Figure 1.

40 Figure 4 is a section on line 4—4 Figure 1.

Referring to the figures by characters of reference 1 designates a base which can be suitably ornamented and preferably mounted on legs 2. This base is provided with a 45 central opening 3 rectangular to receive a rectangular stem 4 provided at the lower end of the standard portion 5 of the pedestal. The walls of this pedestal taper downwardly toward the base and are formed with a shoulders 6 designed to rest on the base.

50 The outer surfaces of the walls may be suitably ornamented and an opening 7 is provided in the upper portion of one wall. This opening is adapted to be closed by means of one or more doors 8.

The corner portions of the standards are beveled as shown at 9 and are provided with finishing strips 10 made up of molding of any desired configuration. One of these strips has a longitudinal groove 11 in its inner face thus to constitute a conduit through which insulated wires 12 of a lighting system can be extended to a receptacle 13 secured within a cap 14 constituting the top of the pedestal.

An opening 15 is provided in the lower end of the stem or shank 4 for the reception of the tubular outlet 16 of a loud speaker unit 17. From this opening, the inner faces of the walls of the pedestal diverge gradually to a point approximately 14" above the lower end of the standard so that the sound chamber increases in width from approximately $\frac{3}{8}$ " at the lower end to approximately $1\frac{1}{8}$ " at the point *a* which, as before stated, is about 14" above the lower end of the sound chamber 18.

From the point *a* the inner surfaces of the walls of the standards diverge at a greater angle up to a point approximately $26\frac{1}{2}$ " 80 above the lower end of the sound chamber and which point has been indicated at *b*. A shoulder 19 is formed along the inner surface of the back wall at the point *b* and serves to support the lower end of a wall 20 which curves upwardly and forwardly and abuts against the front wall of the pedestal directly over the opening 7. This wall constitutes a sound deflector. The upper end of the pedestal is approximately 85 $8\frac{7}{8}$ " above the point *b* and the walls at the upper ends are approximately $\frac{3}{8}$ " thick and increase in thickness to $1\frac{1}{8}$ " at the point *a*.

The specific measurements have been set forth herein because it has been found important to proportion the pedestal as outlined in order to produce the best possible results. As the sound chamber increases in size the walls become thinner and the resonance of the chamber is thus correspondingly increased while the lower or restricted portion of the chamber is provided with thick walls which reduce to the minimum the vibrations resulting from the reception of sound waves from the unit 17.

By providing the receptacle 13 in the cap 14 of the pedestal it is possible to place on the pedestal a lamp and to insert a plug into the receptacle 13. Or, if desired, a lamp may be built onto the pedestal. In

either instance the wires contained within the pedestal are concealed both within and without.

By swinging the doors 8 the volume of tone issuing from the structure can be regulated, as will be obvious.

What is claimed is:

In a loud speaker the combination with a base, legs supporting the same, there being 10 an opening in the base, of a pedestal including upwardly diverging walls having reduced lower ends cooperating to provide a shank seated within the opening, there being shoulders at the upper end of the shank 15 bearing upon the base, the walls of the pedestal being of varying thickness to provide a lower sound chamber and an upper

sound chamber the walls of which diverge upwardly, the walls of the upper sound chamber diverging at a greater angle than 20 the walls of the lower sound chamber but merging therewith at the meeting ends of the chambers, there being an opening in the lower end of the pedestal for the reception of the loud speaker unit and an opening in the upper end of one of the walls, and a curved deflecting wall back of the last named opening for deflecting sound waves from the upper sound chamber to the opening. 25

In testimony that I claim the foregoing as my own, I have hereto affixed my signature. 30

EARL A. SHANKWEILER.
